UNITED STATES PATENT OFFICE.

OTTO KIRSCHBAUM, OF NEW YORK, N. Y., ASSIGNOR TO ELMS & COMPANY, OF NEW YORK, N. Y., A COPARTNERSHIP.

DESIGN FOR A TEXTILE FABRIC.

40,273.

Specification for Design. Patented Sept. 21, 1909.

Application filed July 27, 1909. Serial No. 509,936. Term of patent 3½ years.

To all whom it may concern:

Be it known that I, OTTO KIRSCHBAUM, a citizen of the United States of America, residing in the borough of the Bronx, New York city, in the county of Westchester and State of New York, have invented a new, original, and ornamental Design for Textile Fabrics, of which the following is a specification, reference being had to the accompanying drawing, forming part thereof.

The figure is a plan view of the fabric, showing my design.

I claim:

The ornamental design for a textile fabric, as shown.

OTTO KIRSCHBAUM,
